UNITED STATES PATENT OFFICE.

GEORGE SZITA, OF SAN ANTONIO, TEXAS, ASSIGNOR OF ONE-HALF TO JAMES B. CUNNINGHAM, OF SAN ANTONIO, TEXAS.

ENGINE HEAD.

Application filed July 28, 1922. Serial No. 578,199.

To all whom it may concern:

Be it known that I, GEORGE SZITA, a citizen of the Republic of Hungary, residing at San Antonio, in the county of Bexar and 5 State of Texas, have invented a new and useful Engine Head, of which the following is a specification.

This invention relates to engine constructions and aims to provide novel means, 10 whereby the usual engine may be converted into an engine of the valve-in-the-head type.

Another object of the invention is to provide an engine of this character wherein the usual valve guides may be utilized as push 15 rod guides employed for transmitting motion of a cam shaft to the rockers of the engine head.

A still further object of the invention is to provide a novel form of rocker whereby 20 a plurality of exhaust valves may operate in proximity to each other and be controlled by a single push rod.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawing:—

35 Figure 1 is an elevational view of an engine constructed in accordance with the present invention, a portion thereof being broken away to illustrate the manner of positioning the push rods.

40 Figure 2 is a plan view of one end of the engine disclosing one of the brackets for supporting rockers.

Figure 3 is a sectional view taken on line 3—3 of Figure 1.

45 Figure 4 is a fragmental elevational view disclosing the upper end of one of the push rods employed for controlling the rockers operating the exhaust valves.

50 Figure 5 is a plan view disclosing one end of a bracket and rocker supported thereby.

Referring to the drawing in detail, the reference character 5 designates an engine block which is formed with valve guide- 55 ways 6.

The head, forming the essence of this invention, is indicated at 7 and is formed with bores 8 to accommodate the push rods 9, the bores 8 being designed to register with the guideways 6.

The head is supplied with exhaust valves 10 arranged in pairs, it being contemplated to provide a pair of exhaust valves for each cylinder of the engine block to insure the 60 exhaust gases passing from the cylinder.

The intake valve is of a construction identical with that of the exhaust valves 10 and is operated by means of the rocker 11. Bracket members 12 support the rockers 11 and rockers 13 that operate the exhaust 70 valve and as shown, the rockers 13 include a main rocker 14, and an inner rocker 15, the main or outer rocker 15 being relatively large and formed with a cut out portion to accommodate the inner rocker 15, whereby the rockers may be operated by a single 75 push rod as shown.

The push rods operating the rockers which in turn control the movements of the exhaust valve, are forked, so that the portion 16 may contact with the outer rocker 14 while the inner extension 15' contacts with the rocker 15 to operate the exhaust valves simultaneously. The valve members are returned to their normal or closed positions by means of the coiled springs 16'. A suitable intake is formed in the head which supplies fuel to the engine cylinders the intake manifold being in communication with the head through the openings 17. 90

It might be further stated that the gasket indicated at 18, is formed with suitable openings to permit the push rods to pass therethrough, and at the same time cover the usual valve seats of the cylinder block 95 indicated at 19.

From the foregoing it will be seen that I have provided an engine head, wherein the usual engine head may be removed and replaced by an engine head constructed in accordance with the invention, converting the usual enclosed valve engine into a valve in the head type.

Having thus described the invention, what is claimed as new is:—

1. An engine head having intake and exhaust openings, pairs of exhaust valves for controlling the passage of exhaust gases from the engine, said exhaust valves being arranged in parallel relation with each 110

other, means for controlling the movements of the valves, said means including an outer rocker formed with an opening, and an inner rocker positioned within the opening, and a push rod for operating the exhaust valves simultaneously.

2. An engine head having intake and exhaust openings, exhaust valves arranged in pairs for controlling the exhaust gases from the engine head, a pair of rockers for controlling the exhaust valves, and a forked push rod cooperating with the rockers for operating the exhaust valves simultaneously.

3. An engine head having intake and exhaust openings, exhaust valves arranged in pairs for controlling the passage of exhaust gases from the engine, intake valves for controlling the passage of fuel to the engine, pairs of rockers, a bracket member for supporting each pair of rockers and a push

rod for operating the valve rockers simultaneously.

4. An engine having intake and exhaust openings, exhaust valves arranged in pairs for controlling the passage of exhaust gases from the engine, a bracket member, an outer rocker member and an inner rocker member supported by the bracket and cooperating with the exhaust valves for operating the same simultaneously, and a push rod having means at its upper end for contacting with the rockers to operate the rockers and exhaust valves simultaneously.

In testimony that I claim the foregoing as my own, I have hereunto affixed my signature in the presence of two witnesses.

GEORGE SZITA.
